UNITED STATES PATENT OFFICE.

JAMES T. WALLIS, OF ALTOONA, PENNSYLVANIA.

DRIVING MECHANISM FOR RECORDING APPARATUS.

1,228,724.

Specification of Letters Patent. Patented June 5, 1917.

Application filed November 8, 1914. Serial No. 870,566.

To all whom it may concern:

Be it known that I, JAMES T. WALLIS, a citizen of the United States, residing at Altoona, in the county of Blair and State of Pennsylvania, have invented a certain new and useful Driving Mechanism for Recording Apparatus, of which the following is a specification.

The invention relates to recording apparatus, and more particularly to such apparatus as employed upon locomotives and cars wherein certain of the parts are driven from the axle of the vehicle upon which the apparatus is mounted. It has for its primary objects; the provision of improved means for securing a drive from the end of the axle; the provision of reliable driving means which can be secured to the end of the axle and which can be placed in the ordinary journal box; and the provision of a drive construction of the character specified in which the parts are securely held against accidental disengagement under the jarring action of the vehicle. One embodiment of the invention is illustrated in the accompanying drawings in which—

Figure 1 is a vertical sectional view through the apparatus, Fig. 2 is an end elevation, with certain of the parts partially broken away, of the axle driving means, and Fig. 3 is a vertical section through the central portion of Fig. 2.

The invention is illustrated as applied to a locomotive in connection with a thermometer for indicating the temperatures of the steam in the steam chest, and since the recording drum is driven from the axle of one of the pairs of wheels, the temperature of the steam in the steam chest at any particular point upon the line can readily be determined by an inspection of the paper strip upon which the record is made. The axle drive of the recording drum is preferable to the clockwork drive heretofore employed since the winding up of the clockwork is eliminated, and for the reason heretofore stated, that it serves to indicate the temperature of the steam in the steam chest at the various points in the route over which the locomotive is driven, which is, of course, not true of the apparatus driven by clockwork.

Referring to the general arrangement of

the parts as indicated in Fig. 1, B is one of the trailer wheels of a locomotive; C is the casing in which the recording apparatus, including the drum, is mounted; D is the journal box of the axle upon which the wheels B are mounted, such journal box containing the driving gearing for operating the drum in the casing C; E is the flexible drive shaft by means of which the drive from the axle is transmitted to the drum in the casing C; and F is the pipe leading from the casing C to the steam chest G whereby movement incident to temperature changes is transmitted to the indicating levers in the casing B, this being accomplished by means of the usual mercury column.

Referring to Fig. 1, it will be seen that the flexible shaft E is driven from the axle 1 in the journal box D by means of the bevel gears 2 and 3 and the drive shaft 4, the upper end of the shaft E being connected to another shaft 5 journaled in the casing C. This shaft 5 has a universal joint connection 6 with a shaft 7, and the recording drum 8 is driven from the shaft 7 through the worm (not shown) carried by the shaft 7, the worm wheel 10, and the spur wheels 11 and 12, the latter being mounted upon the axle of the drum 8.

In order to permit of the disengagement of the worm from the worm wheel 10, the end of the shaft 7 adjacent the worm is carried in a movable bearing 13 pivotally supported upon the lever arm 14. This lever arm 14 is carried upon a shaft 15 mounted in suitable bearings as shown and provided outside the casing C with a handle 16 by means of which the parts may be operated and the worm disengaged from the worm wheel 10 whenever it is desired to throw the recording drum out of gear. A recording lever 17 is arranged so that its upper end works across the paper strip on the drum 8 and this lever 17 is operated thermostatically from the connecting pipe F leading to the steam chest. The mechanism interposed between the end of the pipe F and the lever 17, including the coiled tube and the multiplying mechanism, is not shown since it is well known in the art, and any one of a number of different arrangements may be employed. It will be obvious that the

2
drum may be used for receiving records from other devices aside from the thermometer, and it will be understood that the invention is not limited to the use in connection with a thermometer.

The means whereby the drive from the end of the axle is secured, constitutes another feature of my invention and is shown in enlarged detail in Figs. 4 and 5. The 10 bevel gear 2 is provided with a stem 18 which is screw-threaded into the end of the axle 1, and is also provided with the collar 19. The threading of the stem is either left hand or right hand depending upon the 15 side of the engine upon which the device is used, it being desired that the rotation of the axle in the forward movement of the locomotive should tend to tighten the threaded member rather than to loosen it. 20 A cap 20 is also employed, such cap being shrunk onto the end of the axle and having the flange 21 overlapping the outer edge of the collar 19 so that any unscrewing of the stem 18 is prevented. The cap is also held 25 in position by means of a plurality of screws 22 extending through the cap and threaded into the end of the axle.

In order to provide a journal support and a gear casing, the members 24 and 25 are 30 employed, such members being clamped together by means of the screws 26. The inner edges of these members 24 and 25 interlock with the cap 20 as indicated at 27, so that the gear casing formed by the members 35 24 and 25 is rotative with respect to the axle, but held against endwise movement with respect thereto. It will be noted that the inner edges of the member 24 and 25 overlap the ends of the screws 22, so that 40 the accidental displacement of these screws under the jarring action of the locomotive is guarded against. The shaft 4 is keyed to the gear 3 and is prevented from moving upward by the collar 28 pinned to the shaft 45 4. The upward movement of the gear is also prevented by the stop member 29. The shaft 4 extends upwardly through the slotted portion 30 of the journal box, the lid of the journal box, which is not shown, being 50 correspondingly slotted.

The construction of the apparatus is such that it may be placed in the ordinary journal box, the only change required being the provision of the slot in the journal box 55 and the lid for the passage of the shaft 4. The use of the device does not interfere with the proper packing of the journal box, and its construction is such that the parts may be readily assembled or disassembled. The 60 gears are protected from accident, and practically all danger of accidental disengagement of the parts is eliminated due to the manner of securing the stem 18 against unscrewing and to the method of securing the 65 cap in position and guarding against the

displacement of the screws 22. Other advantages of the construction will be readily apparent to those skilled in the art.

What I claim is:

1. In combination in an axle driving 70 means for a recording instrument, an axle, a journal box, a journal member mounted for rotation upon and with respect to the end of the rotating axle independent of the journal box, a pair of intermeshing gears, 75 one carried non-rotatively upon the end of the axle, and the other carried by the journal member, a shaft for said other gear extending transversely of the end of the axle and held against rotation with the axle, and 80 driving connections with the shaft adapted to operate the recording apparatus.

2. In combination in a driving mechanism for recording apparatus mounted upon a vehicle having a rotating axle, a bevel gear 85 secured to the end of the axle and non-rotatable with respect thereto, a journal member mounted for relative rotative movement upon the axle, a bevel gear and drive shaft carried by the journal member with the 90 bevel gear in engagement with the first gear, and driving connections with the shaft adapted to operate the recording apparatus.

3. In combination in a driving mechanism for recording apparatus mounted upon 95 a vehicle having a rotating axle, a bevel gear secured to the end of the axle and non-rotatable with respect thereto, a journal casing mounted for relative rotative movement upon the end of the axle, a second bevel gear 100 carried in the casing and meshing with the first gear, a drive shaft for the second gear, means for preventing the shaft from turning with the axle, and driving connections with the shaft adapted to operate the recording apparatus. 105

4. In combination in a driving mechanism for recording apparatus mounted upon a vehicle having a rotating axle, a bevel gear having a stem threaded into the end of the 110 axle, a retaining member for the gear secured rigidly to the end of the axle, a two part journal member mounted for relative rotative movement upon the retaining member and having a dove-tailed engagement 115 therewith, means for securing the two parts of the journal member detachably together, a bevel gear provided with a shaft and meshing with the first gear, and driving connections with the shaft adapted to operate 120 the recording apparatus.

5. In combination in a driving mechanism for recording apparatus mounted upon a vehicle having a rotating axle, a bevel gear having a stem threaded into the end of the 125 axle, a cap fitting over the end of the axle and overlapping a part of said stem and preventing its unscrewing, screws extending through the cap and into the end of the axle, a two part journal member having a dove- 130

tailed engagement with the said cap and overlapping the screws, means for securing the two parts of the journal member together, a bevel gear provided with a shaft 5 carried by the journal member and meshing with the first gear, and driving connections with the shaft adapted to operate the recording apparatus.

In testimony whereof I have hereunto signed my name in the presence of the two 10 subscribed witnesses.

J. T. WALLIS.
